UNITED STATES PATENT OFFICE.

EMIL SPIEGEL, OF WARNSDORF, AUSTRIA-HUNGARY.

PROCESS OF MAKING LEATHER TIRES.

1,150,715.

Specification of Letters Patent.

Patented Aug. 17, 1915.

Application filed February 8, 1913. Serial No. 747,151.

To all whom it may concern:

Be it known that I, EMIL SPIEGEL, manufacturer, a subject of the Emperor of Austria-Hungary, and a resident of No. 1395, 5 Warnsdorf, Bohemia, in the Empire of Austria-Hungary, have invented a Process of Making Leather Tires; and I do hereby declare the following to be a full, clear, and exact description of the invention, such as 10 will enable others skilled in the art to which it appertains to make and use the same.

This invention relates to a process of making leather tires from leather plates arranged in a row in the groove of the wheel rim and permanently firmly pressed against each other, in such a manner that, after placing the leather plates in the grooves of the rim, the moisture contained in the same is withdrawn from them as completely as 15 possible, by drying them in a drying kiln, and the plates are closely arranged together or pressed against each other in the groove of the rim, by driving in wedges and replacing the same by leather plates, the pressure being still maintained, in such a manner 20 that after having taken up the moisture of the air, or after treatment in a soaking bath, there is produced an exceedingly powerful pressure which is not liable to become 25 reduced.

Reference to be had to the accompanying drawings forming part of this specification in which similar letters of reference indicate 30 corresponding parts in both figures, and wherein—

Figure 1 is a front elevation of a wheel provided with a tire embodying my invention, and Fig. 2 is partly a side elevation and partly a cross-section of the same.

The process can be carried out in the following manner: The plates α are put in as closely as possible in a non-dried state and firmly compressed by hand or by some suitable mechanical press device, whereupon the 40 whole wheel is brought into the drying kiln, where it is left until the leather is deprived of moisture, as completely as possible, which becomes noticeable owing to the appearance 45 of numerous gaps between the leather plates. The wheel β is then again fixed in the device 50 for inserting the plates, and on the whole circumference, at suitable distances apart, are driven in as much as possible chisel-like 55 wedges. These wedges are then replaced by leather plates, without relaxing the pressure

so that the wheel rim is again completely closed with high pressure.

The groove c in the wheel is a dove-tail groove, and the plates α are placed therein as follows: A plate α is placed in the groove c 60 with the plane of the plate extending longitudinally of the plane of the wheel and the plate then turned so as to extend transversely of the plane of the wheel. This will be repeated for each successive plate placed 65 in the groove until enough plates less, say, three or four, to make a complete tire, are in the groove. The last 3 or 4 plates α are then introduced into the groove c in correct position obliquely from above, one end of their 70 dove-tailed extension being first put in inclined direction into the groove and the other end of the dove-tail still projecting being then pressed in by means of a small piece of iron. This latter operation is quite 75 easy since the leather plate is elastic and therefore the small corner of the dove-tail of the plate which is pressed in will reoccupy its natural straight position immediately 80 after having been introduced into the groove. Some strokes with the hammer will then bring the plates into their final position.

After drying the wheel and driving in the chisel-like wedges between the plates, the 85 wedges are turned laterally and slowly withdrawn and simultaneously leather plates are introduced from the side into the resulting gap of the rim, viz. by putting them again with one end of the dove-tail in the groove 90 whereupon the other end is pressed in by means of a small piece of iron and the plates are brought into correct position by some strokes with the hammer. When the wheel 95 is then exposed to the moisture of the air, the renewed expansion of the previously dried plates will produce a very high, hitherto unattained pressure, which is maintained permanently even in a dry atmosphere. 100

The wheels could also be introduced in the known manner into a soaking bath, whereby the swelling would be increased, and the outer layer of the leather plates 105 given an increased hardness and resistance to moisture. Eventually, the drying in the kiln could be repeated, and the wheel introduced, while still hot, into a liquid such as linseed oil, turpentine substitute, varnish, paraffin etc., and left in the same until the 110

leather has swollen up and absorbed as much liquid as possible.

In mechanically compressed tires, and also in leather wheel systems which are exposed only to treatment with soaking liquid, it is impossible to avoid quite reliably the appearance of gaps or cracks, or a loosening of the tire, more particularly in a dry atmosphere. The present process makes it possible, on the contrary, owing to the combination with energetic preliminary drying, to obtain, even without use of mechanical compression, leather tires which remain permanently firm and in a state of tension even in the driest atmosphere.

What I claim as my invention and desire to secure by Letters Patent is:

1. The process of manufacturing leather tires from leather plates, consisting in arranging the leather plates in a row in the groove of a rim, compressing and tightening the plates in the groove of the rim, depriving the leather plates in the groove of the rim of their moisture, adding more plates to the row of leather plates in the groove while the plates are still dry, and maintaining same substantially under constant pressure, and then causing said leather plates in the groove to swell.

Copies of this patent may be obtained for five cents each, by addressing the "Commissioner of Patents, Washington, D. C."

2. The process of making leather tires from leather plates, consisting in arranging and compressing the plates in the groove of a wheel rim, drying the plates thoroughly by bringing the wheel with the plates into a drying kiln, completing the tire by inserting more plates between sundry of the dried and shrunken plates and compressing again the plates in the groove of the wheel rim and then causing said leather plates in the groove to swell.

3. The process of making leather tires from leather plates, consisting in forming a tire on a rim by compressing and tightening the plates in the groove of a wheel rim, then depriving the leather plates of their moisture, adding more plates to the rim to fill the gaps in the tire caused by shrinkage of said plates, and then saturating the tire with a suitable compound to cause said plates to swell.

In testimony whereof I have signed my name to this specification in the presence of two subscribing witnesses.

EMIL SPIEGEL.
